Primary Examiner — Darlington Ly(74) *Attorney, Agent, or Firm* — Michael Best & Friedrich LLP(57) **CLAIM**

We claim the ornamental design for a power tool, as shown and described.

DESCRIPTION

FIG. 1 is a front perspective view of a power tool showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The present application is directed to the design illustrated in the figures. The broken lines shown in the figures illustrate portions of the power tool and form no part of the claimed design.
